UNITED STATES PATENT OFFICE.

HANS P. ANDERSON, OF HOPE, NORTH DAKOTA.

GAME APPARATUS.

1,181,054.

Specification of Letters Patent. Patented Apr. 25, 1916.

Application filed October 26, 1915. Serial No. 58,016.

To all whom it may concern:

Be it known that I, HANS P. ANDERSON, a citizen of the United States, residing at Hope, in the county of Steele and State of North Dakota, have invented a new and useful Game Apparatus, of which the following is a specification.

This invention relates to game apparatus of the "box ball" type, wherein the pins or targets are suspended above the end portion of an alley and adapted to swing when hit by a ball.

One of the objects of the invention is to provide improved means for resetting the pins or targets after they have been shifted out of their normal positions, the resetting mechanism being operated by the player located at that end of the alley remote from the pins.

20 A further object is to provide a novel arrangement of targets or pins whereby it is rendered more difficult to strike all of the said pins or targets and shift them out of their normal positions.

25 Another object is to provide cushioning means whereby the game is rendered practically noiseless.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed, can be made within the scope of what is claimed, without departing from the spirit of the invention.

In the accompanying drawings the preferred form of the invention has been shown.

In said drawings:—Figure 1 is a side elevation of the complete apparatus. Fig. 2 is a plan view of the targets or pins, their resetting apparatus, and other adjacent parts, one of the pins or targets being shown 45 out of its normal position. Fig. 3 is a section on line A—B Fig. 2. Fig. 4 is a section on line C—D Fig. 3. Fig. 5 is a perspective view of a portion of one of the pin controlling springs and its connection.

Referring to the figures by characters of reference 1 designates an alley inclined upwardly away from one end to a substantially horizontal portion 2 above which is arranged a supporting frame 3. This supporting frame includes transverse beams 4

connected by longitudinal beams 5. These longitudinal beams are parallel and are spaced apart sufficient distances to receive between them rows of pins or targets 6 preferably shaped to follow the conventional outline of a ten pin with the exception that the back portion of the pin or target is flattened. Four rows of these pins or targets are employed, there being three pins 60 in each row and the corresponding pins of the several rows alining transversely. The transversely alining pins are mounted on pivot rods 7 extending through the longitudinal beams 5 and are adapted to swing 65 independently upon the rods. Arranged upon the back of each pin at a point adjacent the pivot thereof is a bearing member 8 preferably forked as shown in Fig. 5 and which engages one end of a spring strip 9 70 the other end of which is secured to the next adjoining cross beam 4. Each spring 9 is so positioned relative to its pin or target 6 and beam 4 as to hold said pin or target in either of two positions, to wit, normal or 75 set position, or raised or inactive position. In Fig. 3 one of the pins has been shown in raised or inactive position, it being held there by its spring 9 while the other pins 80 have been shown in their normal or set position where they are held by their springs 9. 85

Secured upon certain of the longitudinal beams 5 are stop strips 10 which extend transversely of the beams 5 and back of the upper portions of the pins 6 so as to limit 90 the forward movement of the lower ends of the pins. These stop strips 10 may be provided with cushioning means indicated at 11 and which cushioning means may be 95 formed of rubber, felt or other like material.

Slidably mounted on certain of the longitudinal beams 5 so as to extend between the rows of pins 6 are strips 12 mounted in suitable guides 13, these strips being arranged at 100 the ends of a cross head 14. Springs 15 connect the front ends of the strips 12 to the front cross beam 4 and serve to hold said strips normally drawn forward. Straps 16 connect strips 12 to the adjacent pins 6 and when the strips 12 and the pins are in their normal positions, these straps will hang 105 loose as shown in Fig. 3.

Connected to the cross head 14 is an actuating cord 17 or other suitable flexible element which is extended around guide sheaves 18 suitably located and forwardly 110

to a lever 20 arranged where it can be conveniently grasped and actuated by the player. By pulling on this lever motion will be transmitted through the flexible connection 17 to the head 14 and the strips 12 will be drawn rearwardly thus pulling through straps 16 upon all of the targets so as to swing the lower ends of the targets downwardly, thus shifting the springs 9 past their dead centers so that they will yieldingly hold the targets in their set or upstanding positions. In order to deaden the sound produced by balls striking the pins, cushions 21 are placed upon the lower end 15 portions of the pins. These cushions also serve to engage the cross beams 4 and reduce the sound produced by the pins shifting to their inactive positions. Additional cushioning means 22 may be arranged on the 20 beams 4 for engagement by the upper ends of the pins 6.

A cushion 23 is loosely suspended back of the pins 6 and is adapted to limit the movement of the balls longitudinally of the alley 25 after they have passed the pins 6. This cushion 23 is suspended above inclined floor sections 24 located back of and below the rear end of the horizontal portion 2 of the alley and said floor sections are designed to 30 direct the balls into return chutes 25 extending along the sides of the alley and from one end to the other thereof. Gutters 26 may be arranged along the sides of the alley as shown for the reception of balls leaving 35 the alley before reaching the pins so that said balls will not be capable of jumping back onto the alley and displacing any of the pins. These gutters discharge onto the inclined floor sections 24.

40 In order that the pins may be set by means of lever 20 without danger of breaking the flexible connection 17, a coiled spring 27 is preferably made a part of said connection so as to yield during the actuation of the 45 lever, after the pins have been set.

It will be noted that the pins are disposed in four parallel rows, there being three pins in each row. The game is played in the same manner as ordinary "box ball," the 50 balls being propelled along the alley in an effort to shift all of the pins out of their normal positions to their raised or inactive positions. By providing the particular cushioning means described, the game can be 55 rendered practically noiseless. A large amount of noise can also be eliminated by providing the alley with a covering of linoleum or other sound deadening material, as indicated at 28.

60 As before pointed out, when one of the pins is struck it will swing upwardly so as to move the bearing 8 past its dead center and bring the spring 9 to position to hold the pin in elevated position. As the strap 65 16 is slack when the pin is in its normal po-

sition, it will permit this swinging movement of the pin. When it is desired to reset the pins it is merely necessary to actuate lever 20 as before pointed out, whereupon the strips 12 will pull through the various 70 straps 16 upon the pins and restore them to their normal or upstanding positions.

What is claimed is:—

1. Game apparatus including an alley, parallel rows of pins suspended above one end portion thereof, there being an equal number of pins in each row and the corresponding pins in the several rows alining transversely, means connected to each pin for holding it in either of two positions, connected slidable members extending between the rows of pins, flexible connections between said members and the pins, and means for shifting said slidable members to transmit motion through the flexible connections to the pins. 80

2. Game apparatus including an alley, parallel rows of pins suspended above one end portion thereof, there being an equal number of pins in each row and the corresponding pins in the several rows alining transversely, means connected to each pin for holding it in either of two positions, connected slidable members extending between the rows of pins, flexible connections between said members and the pins, means for shifting said slidable members to transmit motion through the flexible connections to the pins, and yielding means for returning the slidable members to their initial positions after the pins have been shifted. 90

3. Game apparatus including a frame made up of transverse and longitudinal beams, an alley extending under the frame, parallel rows of pins pivotally mounted in the frame, there being an equal number of pins in each row, the corresponding pins of the several rows alining transversely, yielding held strips slidably mounted upon the frame and extending between the rows of pins, flexible connections between said strips and the pins, an actuating lever, and a connection between said lever and the slidable strips for simultaneously actuating said strips to shift the pins simultaneously to set 110 positions. 115

4. In game apparatus, the combination with an alley and a frame extending over one end portion of the alley and including longitudinal and transverse beams, of parallel rows of pins pivotally mounted between the beams, yielding means connected to each pin for holding it in either of two positions, cushioning means upon the transverse beams for engagement by the pins when shifted 120 out of their normal positions, cushioning means carried by the lower end portions of the pins for engagement by a ball when the pins are in their normal positions and for engagement with the cross beams when the 125 130

pins are out of their normal positions, and means for simultaneously shifting the pins into their normal positions.

5. In game apparatus, the combination with an alley and a frame extending over one end portion of the alley and including longitudinal and transverse beams, of parallel rows of pins pivotally mounted between the beams, yielding means connected 10 to each pin for holding it in either of two positions, cushioning means upon the transverse beams for engagement by the pins when shifted out of their normal positions, cushioning means carried by the lower end 15 portions of the pins for engagement by a

ball when the pins are in their normal positions and for engagement with the cross beams when the pins are out of their normal positions, means for simultaneously shifting the pins into their normal positions, and 20 cushioning means for engagement by the pins when in their normal positions.

In testimony that I claim the foregoing as my own, I have hereunto affixed my signature in the presence of two witnesses.

HANS P. ANDERSON.
